UNITED STATES PATENT OFFICE.

DANIEL HARRIS, OF SALISBURY, MISSOURI, ASSIGNOR TO THE SALISBURY TOBACCO COMPANY, OF SAME PLACE.

DESIGN FOR A TOBACCO-PLUG.

SPECIFICATION forming part of Design No. 21,097, dated October 6, 1891.

Application filed August 13, 1891. Serial No. 402,562. Term of patent 14 years.

To all whom it may concern:

Be it known that I, DANIEL HARRIS, of Salisbury, in the county of Chariton and State of Missouri, have invented and produced a new and original Design for a Tobacco-Plug, of which the following is a specification, reference being had to the accompanying drawing, forming part thereof, in which the figure is a perspective view of a rectangular plug of tobacco embodying my new design.

The design consists of the grooved side surfaces of the plug, the grooves ranging diagonally to the edges between which they extend. Thus a indicates the grooves, and a' ribs or

ridges which alternate therewith, and are produced upon the surface of the plug, as distinguished from being produced by bending the plug. The grooves and ridges range diagonally, and are parallel throughout the whole side surfaces, as shown. Only one side surface is shown, as both are identical.

I claim—

The design for a tobacco-plug herein shown and described.

DANIEL HARRIS.
